RAZOR

August J. England, Providence, R. I.

Application February 21, 1935, Serial No. 7,539

17 Claims. (Cl. 30—30)

This invention relates to a shaving equipment; and has for one of its objects the provision of a complete shaving unit for limited use, consisting not only of the razor but also of sufficient shaving cream for at least one shave.

Another object of the invention is the provision of a razor constructed in a very inexpensive manner so that the same may be cheaply sold and discarded after a single use and having sufficient shaving cream available in the handle thereof for a single shave.

Another object of the invention is the provision of a shaving unit the construction of which will be such that it will be very efficient in use and yet one which may be dispensed in an automatic vending machine at a price sufficiently low so that after a single use the same may be discarded in the same manner as a paper drinking cup.

Another object of the invention is to form the blade holding portion and the shaving paste holding portion all in a single piece, pressed and cut out so that these portions will perform the desired functions.

Another object of the invention is the holding of the blade in place by a simple and yet effective construction by the deflecting of the parts of the material from which they are made and thus eliminating adhesives, screws, rivets, staples or the like.

Another object of the invention is the provision of a holder of a combustible material such as paper so that this holder may be simply and completely destroyed or discarded in a waste paper basket.

With these and other objects in view, the invention consists of certain novel features of construction, as will be more fully described, and particularly pointed out in the appended claims.

In the accompanying drawing:

Fig. 1 is a plan view looking at one side of the unit;

Fig. 2 is a side elevation thereof;

Fig. 3 is a central section on line 3—3 of Figure 1;

Fig. 4 is a plan view of the blank which is formed with the deflected portions therein;

Fig. 5 is a sectional view on line 5—5 of Figure 4;

Fig. 6 is a similar section also through a blade mounted in position;

Fig. 7 is a sectional view through the handle at the location designated 7—7 of Figure 4;

Fig. 8 is a sectional view on line 8—8 of Figure 3;

Fig. 9 is a perspective view of the unit with a cover partly detached, which cover seals the shaving paste in the handle;

Fig. 10 is a perspective view of the unit showing the first finger of the hand as in a position about to remove the cream for use.

Occasionally when one is away from home, either unexpectedly or due to lack of sufficient forethought, he is without the usual equipment necessary for shaving. The tendency of the day is towards lessening the difficulty of such a situation and frequently vending machines are available for the purchase of such small articles as may be desired when traveling and which are easily forgotten by one traveling; and in order to fill a want such as indicated above, I have provided a very cheap razor which may be sold by means of an automatic vending machine; and I have equipped the razor with a sufficient quantity of paste or shaving cream for a single shave, the entire unit being so designed that it may be sold at a price so cheap that the razor may be discarded after it is once used, a blade being permanently mounted therein and not intended for removal for drying; and I have accomplished these results by forming this holder for the blade and the cream out of paper or some compressible material which can be stiffened by suitable treatment and preserved by waxing or the like; and the following is a more detailed description of the present embodiment of this invention, illustrating the preferred means by which these advantageous results may be accomplished:

With reference to the drawing, I have shown in Figure 4 a sheet of material of the general outline or configuration which I blank out from some heavy paper. This blank is then pressed in dies to deflect it into a trough-shaped handle 15 with edge flanges as at 17 and ribs 16 which are cut out at their ends to form fingers 18. The marginal edges are also raised and extended to provide the fingers 19 at a projection beyond the end of the blade holder portion 23 of the blank at the edges thereof. This blade holder portion is bent at an acute angle along line 35, as shown in Figure 2, prior to hardening so that the ribs extending across this bend stiffen the bend materially.

The trough-shaped handle is of a configuration as illustrated at 20 in Figure 7, with generally diverging side walls 21 from a base 22 along a portion adjacent the blade holder part 23, while the end portion of the handle is half round as at 24 with its bottom wall extending upwardly at 25 at the end thereof. The flange 17 is carried

inwardly and downwardly as at 26 between the portions which change shape so that when the shaving paste or cream 38 is positioned in the handle along the semi-cylindrical portion, a transparent cover of "Cellophane" or some such substance designated 31 may be laid over the top of the paste 38 to engage the flange 17 and extend downwardly along the incline 28 to the flat surface 22 at the bottom of the trough. The shaping of this portion 24 of the trough which holds the paste is such that a finger of the user's hand designated 32 in Figure 10, may conveniently fit into the trough and scoop the paste therefrom for application to the face.

15 The paper which I use is treated so as to become stiff when cold, and the trough-shaped formation and ribs serve to stiffen the same very materially and at the time of formation of the trough and bending of the blade holding portion 20 28 along the line 35 so as to dispose it at an acute angle as at 36, see Figure 2. I also position in the bent portion 37 the blade 38 with its upper edge 39 beneath the fingers 18 which are bent outwardly away from the base portion 28 so as to 25 receive and grip the blade and the fingers 19 which extend along the same surface of the blade as do the fingers 18 and are also bent as at 40 before they become set about the cutting edge 41 thereof. These fingers 18 also serve as a guard 30 to prevent the corners of the blade from digging into the flesh of the user. In this manner, the blade is secured in place when the holder finally cools or sets in position, thus firmly securing the blade without use of adhesive or staples or other 35 separate devices.

35 A tab 43 on the end of the cover extends beyond the end of the handle, as shown in Figure 1, for convenient access to be grasped by the fingers and pull the cover from its position, leaving 40 a complete exposure of the paste and easy access thereto for use. This cover is sealed in position by paraffine wax along its peripheral edges, and in fact the entire device is dipped in paraffine wax so as to repel moisture maintaining the entire 45 structure stiff and in the form it is desired the same shall remain for its most effective usefulness. The dipping into paraffine wax also serves to preserve the blade against rust, and the same is easily melted or washed off by hot water 50 when it is desired to use the razor.

Further, the structure is made of paper and is combustible except for the metal blade which being relatively small permits the entire structure to be safely deposited in the waste paper basket 55 for disposal.

The foregoing description is directed solely towards the construction illustrated, but I desire it to be understood that I reserve the privilege of resorting to all the mechanical changes to which 60 the device is susceptible, the invention being defined and limited only by the terms of the appended claims.

I claim:

1. A shaving unit comprising a holder having 65 a razor blade mounting structure at one end and a trough-shaped handle extending therefrom, a razor mounted at said mounting end, shaving cream in the trough of said handle, and a detachable cover extending lengthwise of said handle and covering said cream.

2. A shaving unit comprising a holder having 70 a razor blade mounting structure at one end and a trough-shaped handle extending therefrom, a razor mounted at said mounting end, shaving cream in the trough of said handle, a detachable 75

cover extending lengthwise of said handle and completely covering said cream, and means along the peripheral margin of said cover for sealing the same in place to form an air tight pocket for said cream.

3. A shaving unit comprising a holder having a razor blade mounting structure at one end and a trough-shaped handle extending therefrom of a shape to accommodate the end portion of the human finger for removing a paste therefrom, a 10 razor mounted at said mounting end, shaving cream in the trough of said handle, and a detachable cover extending lengthwise of said handle and covering said cream.

4. A shaving unit comprising a holder having 15 a razor blade mounting structure at one end and a trough-shaped handle extending therefrom of a shape to accommodate the end portion of the human finger for removing a paste therefrom, a razor mounted at said mounting end, shaving 20 cream in the trough of said handle, and a detachable cover extending lengthwise of said handle and covering said cream, the end of said handle being inclined up to the edge thereof.

5. A shaving unit comprising a holder having 25 a razor blade mounting structure at one end and a trough-shaped handle extending therefrom of a shape to accommodate the end portion of the human finger for removing a paste therefrom, a razor mounted at said mounting end, shaving 30 cream in the trough of said handle, a detachable cover extending lengthwise of said handle and covering said cream, and means along the peripheral margin of said cover for sealing the same in place to form an air tight pocket for said 35 cream.

6. A shaving unit comprising a holder having a razor blade mounting structure at one end and a trough-shaped handle extending therefrom, said mounting portion being disposed at an acute 40 angle to said handle, and ribs reinforcing said angular formation and together with the shape of said handle forming a non-collapsible relative stiff structure.

7. A shaving unit comprising a holder having 45 a razor blade mounting structure at one end and a trough-shaped handle extending therefrom, said mounting portion being disposed at an acute angle to said handle, and ribs reinforcing said angular formation and together with the shape of said 50 handle forming a non-collapsible relative stiff structure, the receiving portion of said handle being on the side of the handle toward the blade.

8. A shaving unit comprising a holder having a razor blade mounting structure at one end and 55 a trough-shaped handle extending therefrom, a razor mounted at said mounting end, shaving cream in the trough of said handle, and a detachable cover extending lengthwise of said handle and covering said cream, said holder being read- 60 ly combustible for easy disposal thereof.

9. A shaving unit comprising a holder having a razor blade mounting structure at one end and a trough-shaped handle extending therefrom, a razor mounted at said mounting end, shaving 65 cream in the trough of said handle, and a detachable cover extending lengthwise of said handle and covering said cream, said holder being of paper suitably treated to stiffen the same and render it moisture-repellant.

10. A shaving unit comprising a holder having 70 a razor blade mounting structure at one end and a trough-shaped handle extending therefrom, a razor mounted at said mounting end, shaving cream in the trough of said handle, and a detach- 75

able cover extending lengthwise of said handle and covering said cream, said handle having an abutment surface between its end and the blade extending to the bottom of said trough for the support of said cover.

5 11. A shaving unit comprising a holder having a razor blade mounting structure at one end and a trough-shaped handle extending therefrom, a razor mounted at said mounting end, shaving cream in the trough of said handle, and a detachable cover extending lengthwise of said handle and covering said cream, said cover being of transparent material.

10 12. A shaving unit comprising a holder having a razor blade mounting structure at one end and a trough-shaped handle extending therefrom, a razor mounted at said mounting end, shaving cream in the trough of said handle, and a detachable cover extending lengthwise of said handle and covering said cream, and a tab on said cover extending beyond the end thereof for easy removal of the cover from position.

15 13. A safety razor comprising a handle with an acute angle blade holder portion, a blade, said holder portion provided with a plurality of fingers extending over the upper edge of the blade and forcing it against said mounting portion, some of said fingers being adjacent the ends of the blade and continuous across its width and hooking over the cutting edge and corner thereof to prevent the blade corners from contacting the user.

20 14. A safety razor comprising a handle with an acute angle blade holder portion, a blade,

said holder portion provided with a plurality of guard fingers on one side of the blade protruding therebeyond, and a plurality of fingers extending over the upper edge of the blade and forcing it against said mounting portion, some of said fingers being adjacent the ends of the blade and continuing across its width and hooking over the cutting edge thereof.

25 15. A safety razor comprising a handle with an acute angle blade holder portion, a blade, said holder portion consisting of a single piece of sheet stock, said blade resting thereon, a plurality of fingers raised from the stock of said holder portion and extending over the other side of said blade, two of said fingers adjacent the ends of the blade being longer than the others and continuing across its width and bent over the cutting edge thereof to hold the blade in place.

16. In a toilet unit, an implement at one end and a trough-shaped handle extending therefrom, a paste in the trough of said handle, and a detachable cover extending lengthwise of said handle and covering said paste.

20 17. In a toilet unit, an implement at one end and a trough-shaped handle extending therefrom, a paste in the trough of said handle, a detachable cover extending lengthwise of said handle and covering said paste, and means along the peripheral margin of said cover for sealing the cover in place to form an air tight pocket for said paste.

AUGUST J. ENGLAND.
